UNITED STATES PATENT OFFICE.

ANTONIO C. PESSANO, OF PHILADELPHIA, PENNSYLVANIA, ASSIGNOR TO
THE GEORGE V. CRESSON COMPANY, OF SAME PLACE.

DESIGN FOR A BRACKET-HANGER.

SPECIFICATION forming part of Design No. 32,585, dated April 24, 1900.

Application filed March 19, 1900. Serial No. 9,337. Term of patent 14 years.

To all whom it may concern:

Be it known that I, ANTONIO C. PESSANO, of the city and county of Philadelphia and State of Pennsylvania, have invented a new and 5 original Design for Bracket-Hangers, of which the following is a specification.

The accompanying drawing shows a perspective view of a bracket-hanger embodying my design.

10 A is the vertical body, from which springs the horizontal bracket B, having a curved or arched under surface *b* and terminating at the outer end in a yoke C. The yoke C is curved at the top, and the sides *c c* are connected by a transverse piece D. The top of 15 the curved yoke C and the transverse cross-piece D are provided with bosses *d d*, and small bosses *e e* are located on the sides *c c*.

The essential features of the design are the horizontal bracket B, springing from the body 20 *A* and having the curved undersurface *b*, and the yoke C, located at the end of the bracket and having the ends of its sides *c c* connected by the cross-piece D.

What I claim as new, and desire to secure 25 by Letters Patent, is—

The design for a bracket-hanger, substantially as described and shown in the accompanying drawing.

In testimony of which invention I have here- 30 unto set my hand.

ANTONIO C. PESSANO.
